UNITED STATES PATENT OFFICE.

ROLLIN McDOWELL, OF PORTLAND, OREGON.

CHILD'S VEHICLE.

1,391,554.

Specification of Letters Patent. Patented Sept. 20, 1921.

Application filed December 14, 1920. Serial No. 430,704.

To all whom it may concern:

Be it known that I, ROLLIN McDOWELL, a citizen of the United States, residing at Portland, in the county of Multnomah and State of Oregon, have invented new and useful Improvements in Children's Vehicles, of which the following is a specification.

This invention relates to amusement devices, particularly to toy vehicles, and has for its object the provision of a pedal propelled device formed to represent an aeroplane, the toy having its steering means formed as the tail of an aeroplane and having novelly arranged power transmitting mechanism whereby it may be readily propelled by the feet of the child or other person using the device.

Another object is the provision of a toy of this character upon the front of which is mounted a propeller which is rotated when the device is propelled along the ground or other surface whereby to increase its resemblance to an aeroplane.

An additional object is the provision of a toy of this character which is adjustable for use by children of different sizes, which will be comparatively simple and inexpensive in manufacture, amusing in use, efficient in operation, and a general improvement in the art.

With the above and other objects and advantages in view, the invention consists in the details of construction to be hereinafter more fully described and claimed and illustrated in the accompanying drawings in which

Figure 1 is a plan view of my device,

Fig. 2 is a side elevation thereof,

Fig. 3 is a front elevation,

Fig. 4 is a longitudinal sectional view through the forward portion of the device showing the drive mechanism in detail, and

Fig. 5 is a fragmentary horizontal sectional view illustrating the steering means.

Referring more particularly to the drawings, I have shown my device as comprising a body 10 which is shaped to resemble, more or less, the fuselage of an aeroplane. Secured upon the forward end of the upper edge of this body is a transverse plane 11 which projects appreciably beyond both sides of the body and beneath which is secured a transverse plane 12 parallel therewith and held in spaced relation by suitable struts or posts 13. These planes may be

suitably ornamented with any desired figures such as stars or the concentric circles of contrasting colors so often observable on regular aeroplanes.

Secured to and depending from the lower plane 12 are forwardly inclined supports 14 through which is journaled an axle or shaft 15 carrying wheels 16. Any suitable braces 17 may be employed for reinforcing this structure and rendering the running gear strong and durable. Carried by the body 10 is a suitable seat 18 having a post 19 adjustably mounted so that its height may be varied when the device is to be used by children of different sizes.

Pivoted upon the axle 15 are treadles 20 which are connected by links 21 with crank arms 22 formed on a crank shaft 23 journaled through the brackets or braces 17. The crank shaft 23 has secured thereon a gear 24 which meshes with a pinion 25 on the axle 15. When the pedals 20 are alternately depressed it will be seen that the gear 24 will be rotated and this will naturally result in rotation of the axle 15 and wheels 16 so that the device will be propelled over the ground.

Secured to and extending laterally from the rear end of the body 10 are members 26 which are inactive but which are provided for the purpose of making the device resemble an aeroplane. Secured to or formed on the rear end portion of the body 10 at its upper edge is a tail member 27 which is also inactive but which forms a support for the steering rudder 28 which is formed as a properly shaped board or the like hingedly connected with the rear end of the body, as indicated at 29. The lower end of this member 28 carries a ball bearing roller 30 similar to the wheel of a roller skate. This roller 30, in conjunction with the wheels 16, will outwardly support the device so that it may travel along the ground without likelihood of its tipping over.

Extending upwardly and journaled through the upper wing or plane 11 is a steering post 31 carrying at its upper end a cross bar 32. At its lower end this post 31 is formed with an arm 33 which extends laterally and which is pivotally connected with a link 34 which is in turn pivotally connected with an arm 35 projecting laterally from the tail member 28.

In the use of the device it will be seen

that when a child is seated upon the seat 18 and depresses the treadles 20 with his feet alternately, the crank shaft 23 will be rotated to turn the gear 24 and this will rotate the gear 25 and axle 15 to cause the device to travel. When it is desired to make a turn the operator turns the cross bar 32, and this will result in corresponding movement of the arms of the tail member 28 which will 10 effectually control the course of travel.

Rotatably mounted upon the forward extremity of the body 10 is a propeller 36 which carries a small pulley 37 about which is trained a belt 38 which is in turn trained 15 about a pulley 39 on the axle 15 and the result of this is that when the device is propelled the propeller will be rotated to simulate a real aeroplane.

From the foregoing description and a 20 study of the drawings it will be seen that I have thus provided a simply constructed and very easily operated foot propelled toy designed primarily for use by children and which will on account of its appearance and 25 general construction be extraordinarily attractive as well as affording entertainment and helpful exercise to the user.

While I have shown and described the preferred embodiment of my invention, it is of 30 course to be understood that I reserve the right to make such changes in the form, construction, and arrangement of parts as will not depart from the spirit of the invention or the scope of the subjoined claims.

Having thus described my invention, I 35 claim:

1. A device of the character described comprising a body, a hinged member at the rear end thereof carrying a ground engaging roller, means for swinging said member, an axle journaled below the forward end of the body and carrying ground engaging wheels, a pinion on said axle, a gear journaled below said body and meshing with said pinion, a crank shaft upon which said 45 gear is mounted and provided with crank portions, and treadles pivoted upon the axle and connected by links with said crank portions.

2. A device of the character described 50 comprising a body, a hinged member at the rear end thereof carrying a ground engaging roller, means for swinging said member, an axle journaled below the forward end of the body and carrying ground engaging 55 wheels, a pinion on said axle, a gear journaled below said body and meshing with said pinion, a crank shaft upon which said gear is mounted and provided with crank portions, treadles pivoted upon the axle and 60 connected by links with said crank portions, a propeller journaled upon the forward extremity of said body, and means operated from said axle for rotating the propeller.

In testimony whereof I affix my signature. 65

ROLLIN McDOWELL.
